Primary Examiner—Nelson C. Holtje*Assistant Examiner*—Martie Thompson*Attorney, Agent, or Firm*—Jacobson, Price, Holman & Stern[57] **CLAIM**

The ornamental design for the writing instrument, as shown and described.

DESCRIPTION

FIG. 1 is a left side elevational view of a writing instrument showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view of a second embodiment of my new design, the right side being a mirror image thereof;

FIG. 7 is a front elevational view of FIG. 6;

FIG. 8 is a rear elevational view of FIG. 6;

FIG. 9 is a top plan view of FIG. 6; and,

FIG. 10 is a bottom plan view of FIG. 6.

FIG. 1

FIG. 2

FIG. 3

FIG. 4

FIG. 5

FIG. 6

FIG. 7

FIG. 8

FIG. 9

FIG. 10
